UNITED STATES PATENT OFFICE.

SISSAK K. OUZOUN-BOGHOSIAN, OF WASHINGTON, DISTRICT OF COLUMBIA.

WATCH-ROLLER REMOVER.

1,331,851.

Specification of Letters Patent. Patented Feb. 24, 1920.

Application filed January 27, 1919. Serial No. 273,401.

To all whom it may concern:

Be it known that I, SISSAK K. OUZOUN-BOGHOSIAN, a subject of the Sultan of Turkey, residing at Washington, District of Columbia, have invented certain new and useful Improvements in Watch-Roller Removers, of which the following is a specification.

This invention relates to improvements in watch-roller-remover tools, which are used by watchmakers to remove the roller-table of a watch from the balance staff to which the roller-table is tightly fitted.

The object of my invention is to provide a simple, inexpensive and adjustable roller-remover which is adapted to remove the roller of a large size or a small size watch safely, instantly and without disturbing any delicate part of the balance wheel and the balance staff to which the roller is tightly fitted.

This roller-remover is an adjustable tool, the two jaws of which can be readily adjusted between the roller and the arm of the balance-wheel, the outside faces of the two jaws of the tool contacting the back of the roller, so that by striking with a hammer the top of the tool on a conical stump having a very small hole to fit the pivot of the balance staff and safeguard the same, the roller can be removed from the balance staff easily and safely.

The nature, characteristic features and scope of the invention will be more fully understood from the following description taken in connection with the accompanying drawings forming part hereof and in which:

Figure 1 is a perspective view of the roller-remover of the invention. Fig. 2 is a perspective view of a modification of the same. Fig. 3 is a side view of the tool of the invention. Figs. 4 and 5 are the back and the front views, respectively, of the tool of the invention, from which the screw-bar and two screw nuts are removed. Fig. 6 is a plan view of the two curved jaws of the roller-remover.

Fig. 7 is a plan view of the screw-bar 8 removed from the roller-remover of the invention, which is taken on an enlarged scale to show the square shoulder 18.

Similar reference characters refer to similar parts in all the figures in the drawings.

Referring to the drawings, in Figs. 1, 2 and 3, two parts 4 and 5 are riveted together by rivets 11, 12. The portions 9, 10 and 14, 15 of the two parts 4 and 5 are reduced to increase the flexibility of the tool.

The screw-bar 8 having the head 16 and a square shoulder 18 close to the head 16 is fitted into the square hole 13 on part 5. The 60 screw-bar 8 loosely passes through the round hole 17 on the part 4. The screw-nut 6 is fitted to the screw-bar 8 and against the square shoulder 18 close to the head 16 of the screw-bar 8, thus tightly securing the screw-bar 8 on the part 5. The screw-nut 7 is fitted to the screw-bar 8 contacting with the part 4 externally. By turning the screw-nut 7, the jaws 1, 2 are adjusted to open and close as may be desired. The two curved 70 jaws 1, 2 have sharp edges, and the slot 3 is provided to protect the cement of the roller-jewel when removing the roller from the balance staff.

Having thus described my invention what 75 I desire to secure by Letters Patent of the United States and claim is:

1. A watch-roller-remover tool comprising two parts 4 and 5 riveted together by rivets 11, 12, said two parts 4 and 5 having two 80 curved jaws 1 and 2 with sharp edges and the slot 3, the portions 9 and 10 of said two parts 4 and 5 being reduced increasing flexibility thereof, a screw-bar 8 having a head 16 and a square shoulder 18 close to said 85 head, being fitted to a square hole 13 on said part 5 by said square shoulder 18 of said screw-bar 8, said screw-bar 8 passing through a round hole 17 on said part 4, two screw-nuts 6 and 7 fitted to said screw-bar 8, said 90 jaws 1, 2 adapted to be adjusted by said screw-nut 7, said tool adapted to remove the roller of a watch from the balance staff of said watch, all substantially as set forth.

2. A watch-roller-remover tool adapted to 95 remove the roller of a watch, said tool comprising two parts riveted to each other, said two parts having two curved jaws, said jaws having sharp edges, one of said two jaws being slotted at the middle, a screw-bar 100 fitted on said two parts, said screw-bar having a head and a square shoulder close to said head, a screw-nut fitted to said screw-bar and against said square shoulder, said screw-bar passing through the second of 105 said two parts through a round hole, another screw-nut fitted on said screw-bar and contacting with said second part externally, the lower portions of said two parts being reduced to increase flexibility thereof, all 110 substantially as set forth.

In testimony whereof I affix my signature.

SISSAK K. OUZOUN-BOGHOSIAN.
